UNITED STATES PATENT OFFICE.

HENRY S. HURLBUT, OF BOSTON, MASSACHUSETTS.

IMPROVEMENT IN BUTTON-HOOKS.

Specification forming part of Letters Patent No. 178,778, dated June 13, 1876; application filed April 5, 1876.

To all whom it may concern:

Be it known that I, HENRY S. HURLBUT, of Boston, in the county of Suffolk and State of Massachusetts, have invented certain Improvements in Button-Hooks, of which the following is a full, clear, and exact description, reference being had to the accompanying drawings, making part of this specification, in which—

Figures 1 and 2 are perspective views of button-hooks constructed in accordance with my invention. Fig. 3 is a section representing the manner of using my improved button-hook.

The ordinary button-hook now in general use is objectionable for the reason that the button is liable to be twisted off by the thread or other fastening being subjected to an undue strain, besides which the shank near the hook is not of a width sufficient to keep the button-hole open to allow of the easy entrance of the button, the contact of the button with the edges of the hole rendering an increased strain on the button necessary, in order to allow of its passage.

My invention has for its purpose to overcome the above-mentioned objections; and consists in a device bifurcated at its extremity, and having the projections at a right angle, or nearly so, to the handle, and a depression in the rear of the bifurcation, and having its shank adapted to open the button-hole to allow of the button being drawn or pried through it with great facility, whereby the button is only subjected to a slight strain, which is not liable to break it, nor the thread or other fastening by which it is secured, the twisting of the button or its fastening, and the obstruction caused by bringing it against the edges of the button-hole incident to the construction and use of the ordinary button-hook, being entirely avoided.

To enable others skilled in the art to understand and use my invention, I will proceed to describe the manner in which I have carried it out.

In Fig. 1 of the said drawings, A represents a flat metal strip of the form seen, one end, *a*, being rounded and somewhat larger than its opposite end *b*, for convenience in handling. The end *b* is bifurcated, as shown at *c c*, turned or rounded up, as seen, the bifurcated end thus formed embracing the button, which, as the instrument is bent over and drawn through the button-hole, as seen in Fig. 3, is brought down to a firm bearing within the depression *d*, the eye or fastening of the button fitting into the space between the projections *c c*, that portion of the shank of the instrument in close proximity to the depression *d* being of such width as to open the button-hole sufficiently to allow of the button being readily drawn through it without being obstructed by contact with the edges, as has heretofore been the case where an ordinary button-hook has been employed.

Instead of making the instrument from a metal plate, as seen in Fig. 1, it may be formed of wire bent into the desired shape, as seen in Fig. 2.

The above-described instrument is exceedingly simple and effective, and by its use the twisting, wrenching off, or breaking of the buttons, and the great annoyance and inconvenience resulting therefrom, are entirely avoided.

What I claim as my invention, and desire to secure by Letters Patent, is—

The within-described button-hook, having the bifurcated end and the projections *c c* bent at a right angle, or nearly so, to the shank or handle A, substantially as and for the purpose specified.

Witness my hand this 22d day of March, A. D. 1876.

HENRY S. HURLBUT.

In presence of—

P. E. TESCHEMACHER,
W. J. CAMBRIDGE.
